UNITED STATES PATENT OFFICE

2,671,003

CABINET CONSTRUCTION

Charles E. Attwood, Chicago, Ill., assignor to
Acme Visible Records, Inc., Chicago, Ill., a corporation of Delaware

Application October 18, 1949, Serial No. 121,935

3 Claims. (Cl. 312—264)

1

This invention relates to improvements in cabinets and refers particularly to a cabinet construction which contemplates rapid assembly and retention of the various components of the cabinet in assembled form with a minimum of retaining means.

One of the important objects of the present invention resides in a cabinet construction wherein the partitions thereof function as spacers and tie-members in holding the front and rear walls of the cabinet together in unitary assembled relationship.

Another important feature of the invention resides in a cabinet construction wherein the partitions, in addition to functioning as hereinbefore described, also serve as partitions per se and supports for slidable drawers.

A further important feature of the invention comprises a cabinet which is held in assembled form by a minimum number of retaining devices.

Other objects and advantages of the invention will be apparent from the accompanying drawings and following detailed description.

In the drawings,

Figure 1 is a longitudinal sectional view of the improved cabinet.

Figure 2 is a transverse sectional view taken on line 2—2 of Figure 1.

Figure 3 is a detailed sectional view taken on line 3—3 of Figure 2.

Figure 4 is a plan sectional view, parts being shown in elevation and parts being broken away, of the improved cabinet.

Figure 5 is a transverse sectional view taken on line 5—5 of Figure 1.

Figure 6 is a fragmentary, detailed, perspective view illustrating the supporting lugs for the front ends of the partitions.

Figure 7 is a fragmentary, detailed, perspective view of one of the partitions.

Referring in detail to the drawings, 1 indicates a cabinet such as those employed in housing visible card index systems. Although the cabinet 1 is specifically adapted for this purpose, it is to be understood that the present invention is not to be limited to the particular use for which the cabinet is adapted since the cabinet may be employed for many other purposes.

The cabinet 1 comprises a front frame portion 2 including an upper rail 3, a lower rail 4 and side rails 5. The frame 2 comprising the defining rails may be of unitary construction and preferably comprises a die-cast casting.

A rear wall 6 is also employed and is spaced from the frame 2. The rear wall 6 comprises a

2

panel 7 having peripheral dimensions corresponding to those of the frame 2. The panel 7 is provided with a peripheral bead 8 and transverse beads 9 which function to reinforce the panel. Disposed centrally of said panel and in vertical alignment is a plurality of apertured bosses 10 and in horizontal alignment with each of the bosses 10 and flanking the bosses 10 on each side, the inner surface of the panel 7 carries a plurality of projections 11 and 12, the projections 11 being in vertical alignment and the projections 12 being in vertical alignment on each side of the column of bosses 10.

A plurality of partitions 13 (Figure 7) connect the frame 2 to the rear wall 6. As will be hereinafter more fully described, the partitions 13 function to divide the cabinet into a plurality of compartments 14; act as spacers between the front frame and the rear wall; act as tie-members securing the front frame to the rear wall and function as supports for drawers which may be housed in the cabinet. Each of the partitions 13 is provided with an upwardly-extending flange 14 at one end and, at the opposite end, the partition is reverse-bent to form a U-shaped gripping member 15.

Upon the inner faces of the opposite side rails 5, a plurality of supporting lugs 16 are mounted one above the other in spaced relationship. The supporting lugs 16 are preferably formed integral with the respective side rails 5, although said lugs may be formed separate and may be secured to the side rails in appropriate spaced relationship by any convenient securing means, such as screws, bolts, rivets or the like.

35 In assembling the front frame 2, rear wall 6 and the partitions 13, the forward edges of the partitions are disposed adjacent the front frame 2 and the U-shaped folds 15 are engaged with the lugs 16, each U-shaped fold engaging one pair of lugs upon opposite faces of the rails 5. The rear upwardly-extending flange 14 of each of the partitions 13 is provided with three apertures, a central aperture 17 and two side apertures 18. In assembling the elements, the flanges 14 of each of the partitions 13 are disposed adjacent the inner face of the rear wall 6 and the projections 11 are brought into supporting registration with the side apertures 18. The central apertures 17 are in alignment with the apertured bosses 10 and bolts 19 are inserted through the apertures in the bosses and the central apertures 17. Nuts 20 may be employed to secure the flanges in snug relationship with respect to the bosses 10. Although bolts are shown and described as comprising the fastening

means, it is to be understood that any other suitable fastening means may be employed such as screws or rivets.

It can readily be seen that the front frame 2 and the rear wall 6 are in the manner hereinbefore described securely fastened together by the partitions 13. By the provision of the inter-engaging projections 11 and side openings 18, the partitions 13 adjacent the rear wall 6 are prevented from rocking about the respective bolts 19. At the front end of cabinet, rocking of the partitions about their longitudinal axes is prevented by engagement with the opposite lugs 16.

To form the side walls, top and bottom of the cabinet, a single piece of sheet material 20 may be, in effect, wrapped around the entire cabinet, the opposite edges of said sheet material engaging upon shoulders 21 carried by the rear wall 6 and shoulders 22 carried by the front frame 2. The wrapped around sheet material 20 additionally functions as a compression member in spacing the front frame 2 from the rear wall 6.

The partitions 13 also function as supports for drawers 23 which may be slidably positioned within the compartments 14, the drawers being moved inwardly and outwardly conveniently by means of handles 24. The drawers 23 may comprise a support for visible index cards (not shown) or may be in the form of conventional drawers.

It can readily be seen that a cabinet construction is herein provided which is characterized by the fact that its assembly comprises essentially the use of a minimum number of retaining devices. In the form of the invention illustrated, five drawers are contemplated and only four retaining bolts 19 are used in assembling the essential portion of the cabinet. Of course, any number of compartments 14 is contemplated and in each case the number of retaining devices will equal the number of compartments minus one. It can also be readily seen that the present construction is particularly adaptable in forming an all-metal cabinet—the front frame 2 and the rear wall 6 may be die-cast and the remaining elements of the cabinet may comprise sheet metal. In order to eliminate play as much as possible, the projections 11 and 12 are preferably tapered so that they snugly engage the apertures 18.

It is to be understood, of course, that as many compartments 14 as desired may be provided in the cabinet separated by partitions 13. The front frame and rear wall of the cabinet are preferably die cast but may be constructed in any other suitable fashion, the present invention being broadly directed to the simplified retaining means regardless of the specific form or materials comprising the structure.

I claim as my invention:

1. A cabinet comprising a front frame, a rear wall spaced from said front frame, an integral member comprising opposite side walls and top and bottom walls carried by said front frame and rear wall, a horizontal partition for said cabinet for holding said front frame and rear wall together, said partition having front and rear portions, means for securing the front portion of the partition to said front frame to render said partition immovable vertically with respect to said frame, means for securing the rear portion of the partition to the rear wall, said last mentioned means comprising an angularly disposed flange carried by the rear portion of the partition, means extending through said flange and said rear wall for engaging an intermediate por-

tion of the flange and an intermediate portion of the rear wall, and a projection carried by said rear wall for removable engagement in an aperture provided in said flange laterally spaced from said intermediate engaged portion of said flange.

2. A cabinet comprising a front frame, a rear wall and an integral sheet metal member which is wrapped around said front frame and rear wall to form opposite side walls, a top and a bottom 10 said front frame bordering said side walls and top and bottom and being completely open therebetween, a partition for said cabinet for holding said front frame and rear wall together, said partition having a front and a rear portion, means for removably securing spaced lateral portions only of the front portion of the partition to said front frame, means for securing the rear portion of the partition to the rear wall, said last-mentioned means comprising an angularly 15 disposed flange carried by the rear portion of the partition, a single fastening means for securing an intermediate portion of the flange to an intermediate portion of the rear wall, and a projection carried by said rear wall on opposite lateral 20 sides of said fastening means for removable engagement with an aperture provided in said flange.

3. A cabinet comprising a front frame, a rear wall spaced from said front frame, an integral 30 sheet metal member wrapped around said front frame and rear wall to form opposite side walls and a top and bottom, said front frame bordering said side walls and said top and bottom walls and being completely open therebetween, horizontal 35 partitions for said cabinet each having front and rear portions, means for removably securing the front portion of each of the partitions to said front frame, said means comprising spaced lugs carried by said front frame adjacent said side 40 walls, and U-shaped means carried by the front portion of said partition for embracing the upper and lower portions of said lugs to prevent vertical movement of said partitions relative to said frame, means for securing the rear portion of each of said partitions to the rear wall, said last-mentioned means comprising an angularly disposed flange carried by the rear portion of each partition, screw means extending through each flange and said rear wall for fastening an intermediate portion of each flange to an intermediate portion of the rear wall, and projections 45 carried by said rear wall for removable engagement in apertures provided in said flanges horizontally spaced from, and at least one on each side of, said intermediate portion of each flange.

CHARLES E. ATTWOOD.
